[57] CLAIM

The ornamental design for a pie crust edge cover, as shown and described.

DESCRIPTION

FIG. 1 is a top perspective view of a pie crust edge cover, showing my new design;

FIG. 2 is a front elevational view, the rear, left side and right side elevational view being a mirror image thereof;

FIG. 3 is a top plan view thereof; and,

FIG. 4 is a bottom plan view thereof.

FIG. 1

FIG. 2

FIG. 3

FIG. 4
